Primary Examiner—Martie K. Holtje(74) *Attorney, Agent, or Firm*—Oliff & Berridge, PLC(57) **CLAIM**

The ornamental design for adhesive dispenser/applicator device, as shown and described.

DESCRIPTION

FIG. 1 is a front/top perspective view of an adhesive dispenser/applicator device showing our new design; FIG. 2 is a rear/bottom perspective view thereof; FIG. 3 is a top plan view thereof; FIG. 4 is a left side elevational view thereof, the right side is a mirror image; FIG. 5 is a bottom plan view thereof; FIG. 6 is a front end view thereof; and, FIG. 7 is a rear end view thereof.

The push button mechanism depicted by means of broken lines in FIGS. 1 through 4 and 6 and 7 has been shown for illustrative purposes only and forms no part of the claimed design.
